UNITED STATES PATENT OFFICE

JOHN FRIEDEL, JR., OF NEW YORK, N. Y.

PEN OR PENCIL ATTACHMENT

Application filed August 24, 1929. Serial No. 388,238.

This invention relates to pen or pencil attachments, and more particularly aims to provide a novel and valuable anti-rolling device, or rest, for pencils, penholders, fountain pens and the like.

Objects of the invention are to provide an anti-rolling attachment which will be substantially rigid, yet extensible to conform to pencil portions of different diameter, and which will effectively prevent the pencil, penholder or the like from rolling off an inclined or other surface while in a horizontal position; which may, when desired, be used to support the implement in a vertical position over the neck of an ink bottle; and which may also be used as a dipping guide for the writing implement.

A further object is to enable the anti-rolling attachment to be made of metal, such as a strip of wire or the like, so that it will include advantages of durability as well as flexibility.

A still further object is to construct the anti-rolling attachment of a continuous strip of wire formed with spring tensioned loops to provide a combined rest and support for the writing implement.

Other objects are to simplify and improve the construction of devices of this general character and to reduce the cost of manufacture. Still other objects and advantages of the invention will be hereinafter specifically pointed out, or will become apparent, as the specification proceeds.

With the above indicated objects in view, the invention resides in certain novel constructions and combinations and arrangements of parts, clearly described in the following specification and fully illustrated in the accompanying drawings, which latter show an embodiment of the invention as at present preferred.

In the drawings:

Fig. 1 is a side elevation partly in section showing a penholder equipped with said embodiment, the latter being used in this instance as a vertical support and dipping guide or rest.

Fig. 2 is a transverse sectional view on the line 2-2 of Fig. 1.

Fig. 3 is a perspective view of a penholder equipped with the device of Fig. 2.

Referring to the drawings, the anti-rolling attachment 11 in this instance is formed of a single strip of wire, which may be of any material such as gold, silver, steel or the like. This strip of wire is preferably tensioned and bent outward commencing at the point indicated at 12 to form an arcuate portion 13 to engage the body 14 of the writing implement and then inward to form a substantially circular loop or coil 15 the lower portion of which also engages the writing implement body. The strip preferably includes alternate arcuate portions 16, 17 and 18, and looped portions 19, 20 and 21; and the ends of the wire strip are, in this instance, secured together by being coiled about each other as indicated at 22.

The arcuate portions 13, 16, 17 and 18 are adapted to surround the body of the writing implement while looped portions 15, 19, 20 and 21 extend outward from the body 14 in a direction preferably at right angles to the longitudinal axis of the body 14. The looped portions are preferably arranged so that their outer peripheries lie in parallel planes. By this means, any two adjacent looped portions may rest on a flat, horizontal or inclined surface to support the writing implement against rolling, as indicated at 23 in Fig. 3.

To enable the anti-rolling attachment to be adjustable in its application to writing implement bodies of different diameter, or different diameter portions on the same body, the present tensioned construction permits the body encircling parts to expand internally, enlarging the compass of the arcuate portions 13, 16, 17 and 18 to accommodate the body, the looped portions 15, 19, 20 and 21 under this condition undergoing a corresponding reduction in size.

Instead of terminating at the point 22 the ends of the wire may be continued to form an extension 24 including an elongated loop 25 and an eye 26, as seen in Fig. 3. This extension 24 is preferably used as a finger piece or handle with which to slide the attachment on or off, or to different positions along, the writing implement body, thereby preventing

soiling of the fingers with ink; or the finger piece may be used as a hanger upon which to suspend the writing implement to the user's clothing.

5 As seen in Fig. 1, the anti-rolling attachment is also useful as a dipping guide to prevent overflowing the pen point. The position of the attachment 11 on the writing implement body 14 determines the depth to which the pen 27 is to be immersed in the writing fluid 28, the pen's entrance into the bottle neck 29 beyond the desired point being restrained by the looped portions or rests 15, 19, 20 and 21.

10 15 When not in use, the writing implement may also be supported in an upright position on the bottle neck 29.

20 The hereinbefore described construction admits of considerable modifications without departing from the invention; therefore, I do not wish to be limited to the precise arrangements shown and described, which are, as aforesaid, by way of illustration merely. In other words, the scope of protection contemplated is to be taken solely from the appended claims, interpreted as broadly as is consistent with the prior art.

What I claim as new is:—

30 1. An attachment for penholders comprising a plurality of loops of resilient wire and intervening arcuate resilient portions integral with the loops to constitute an annular penholder gripping member, the said loops being freely contractible whereby to adapt 35 the annular gripping portion to be fitted to penholders of different diameters.

40 2. An attachment for penholders comprising a plurality of loops of resilient wire and intervening arcuate resilient portions integral with the loops to constitute an annular penholder gripping member, the said loops being contractible whereby to adapt the annular gripping portion to be fitted to penholders of different diameters, the said loops 45 being equi-distantly spaced about the said annular gripping portions whereby a pen tip supported on a penholder will be maintained in elevated position with respect to a desk upon which the holder is disposed.

50 3. An attachment for penholders comprising a strand of wire formed into plurality of loops, and intervening arcuate resilient portions integral with the loops to constitute an annular member, the said loops being contractible whereby to adapt the annular member for resilient gripping engagement 55 with a penholder, said strand being twisted to provide a finger piece to extend along the side of the penholder and constitute means whereby the attachment may be slidably adjusted upon the holder.

60 4. An attachment for a writing instrument comprising a piece of resilient wire having arcuate portions thereon, which latter provide an annular unit for gripping the

body of an instrument at one end of the latter adjacent the writing point of the instrument, interposed loops disposed on the plane of said unit for spacing said end from an adjacent surface, and an elongated loop disposed at right angles to the aforesaid plane and providing a suspension clip.

70 In testimony whereof I have affixed my signature.

JOHN FRIEDEL, JR.
